UNITED STATES PATENT OFFICE.

MARTIN HARTMAN, OF UPPER SANDUSKY, OHIO.

DETACHABLE HANDLE FOR BROOMS, MOPS, &c.

SPECIFICATION forming part of Letters Patent No. 789,021, dated May 2, 1905.

Application filed January 9, 1904. Serial No. 188,301.

To all whom it may concern:

Be it known that I, MARTIN HARTMAN, a citizen of the United States, residing at Upper Sandusky, in the county of Wyandot and State of Ohio, have made certain new and useful Improvements in Detachable Handles for Brooms, Mops, &c., of which the following is a specification.

My invention relates to an improvement in detachable handles for brooms, mops, &c., its object being to provide improved means whereby a handle can be put on a new broom, &c., when the old one is worn out and also to provide improved means whereby the handle can be readily taken apart and packed in a small space, thereby entailing a saving in cost of transportation and shipping.

To these ends my invention consists in certain novel features of construction, arrangement, and combination of parts, as will be hereinafter fully described, and pointed out in the claim, reference being had to accompanying drawings, in which—

Figure 1 is a sectional elevation showing the device as in use. Fig. 2 is a sectional view of the coupling member. Fig. 3 is a sectional view of the stub member, showing the central connecting-bolt.

In carrying out my invention I use a stub or rod (of wood) A of suitable length—say about six inches—having a central bore *a*, preferably square, through it. The upper end of the stub A is cone or wedge shaped, as shown at *a'*. Passing through the central bore is the bolt B, the head *b* of which rests against the lower end of the stub. The upper end of the bolt extends a short distance beyond the upper cone-shaped end of the stub and is threaded, as at *b'*. The body of the bolt is made square or some other suitable shape to prevent its turning in the stub. This stub with the bolt B in place is secured in the broom-head C by wiring or other suitable means.

D represents a casting of suitable length which is preferably hollow throughout its length and formed with an upper socket *d* and a lower socket *d'*. The upper socket is slightly tapered and is designed to receive and hold the lower end of a long broom or mop handle, as will be presently described. The

lower socket *d'* is tapered and cone-shaped, the taper corresponding to that of the cone-shaped upper end of the stub A. A screw-threaded opening *d''* extends from the upper end of the socket *d'* to the lower end of the upper socket *d*, said threaded passage *d''* being adapted to be screwed onto the threaded upper end *b'* of the bolt B.

The handle E has its lower end slightly tapered and fits in the upper socket *d* of the casting D. The handle E may be held from turning in the socket *d* by means of a pin *e* or by other suitable means.

The stub A, with its bolt B, having been securely fastened in the broom or mop head C, the casting D, with the handle E in place, is then fitted over the upper end of said stub and screwed to the threaded end of the bolt B, thus drawing stub and casting or coupling tightly together and forming a joint which will be as strong as any other part of the broom or mop.

When the broom or mop wears out, the stub and handle can be removed therefrom and secured to a new broom or mop, or the casting D, with broom-handle E, can be removed from the broom or mob head when it is desired to place the broom or mop within small compass.

It will thus be seen that I produce a device which is cheap, simple, and convenient in handling and one which will afford considerable saving of material and also space in transportation and shipping.

It is of course obvious that my improvement is equally applicable to mops and the like.

The lower end of the casting or coupling is flared outwardly, as shown in Fig. 2, so as to abut against the upper portion of the wiring of the broom-head and hold it in place.

Having thus described my invention, what I claim as new, and desire to secure by Letters Patent, is—

The herein-described improvement in attachments for separable broom-handles consisting of a hollow stub cone-shaped at its upper end and adapted to be secured in a broom-head, a bolt passing through the center of said stub and having its upper end externally

threaded, a coupling member having a socket in its upper end adapted to receive and retain a handle-stick and provided with a cone-shaped socket in its lower end adapted to fit over the 5 cone-shaped upper end of the stub, said coupling member provided further with an internally-threaded passage extending from the

upper end of the cone-shaped socket and engaging the threaded upper end of the bolt.

MARTIN HARTMAN.
